MOBILE FOOD SERVING UNIT

William G. Hunt, Florence, S. C.

Application November 24, 1954, Serial No. 33,233

Term of patent 14 years

(Cl. D14—3)

To all whom it may concern:

Be it known that I, William G. Hunt, a citizen of the United States of America, residing at Florence, in the county of Florence, State of South Carolina, have invented a new, original, and ornamental Design for a Mobile Food Serving Unit, of which the following is a specification, reference being had to the accompanying drawings, forming a part thereof:

Figure 1 is an isometric view of the mobile food serving unit embodying my new design; and

I claim:

The ornamental design for a mobile food serving unit, substantially as shown.
